UNITED STATES PATENT OFFICE.

JOHN B. DONOVAN, OF NORTH ADAMS, MASSACHUSETTS, ASSIGNOR OF ONE-HALF TO
JAMES K. LANNING, OF FALL RIVER, MASSACHUSETTS.

BUNCH-BUILDER FOR WINDING MECHANISM.

1,255,085.

Specification of Letters Patent. Patented Jan. 29, 1918.

Application filed May 27, 1914. Serial No. 841,360.

To all whom it may concern:

Be it known that I, JOHN B. DONOVAN, a citizen of the United States, and a resident of North Adams, in the county of Berkshire and State of Massachusetts, have invented an Improvement in Bunch-Builders for Winding Mechanism, of which the following description, in connection with the accompanying drawings, is a specification,

10 like characters on the drawings representing like parts.

This invention relates to winding mechanism adapted to build up a yarn package upon a yarn receiver by laying successive 15 layers of yarn upon the receiver progressively and particularly it relates to mechanism for forming a bunch thereon, thereby peculiarly adapting the yarn package for use in feeler looms.

20 In order that the principle of the invention may be readily understood, I have disclosed certain embodiments thereof in the accompanying drawing, wherein—

Figure 1 is a side elevation of a so-called 25 Mason builder or winding mechanism having my invention applied thereto;

Fig. 2 is a plan view of a portion of the mechanism shown in Fig. 1 and upon a larger scale;

30 Fig. 3 is a side elevation of the mechanism shown in Fig. 2;

Fig. 4 is a vertical cross section upon the line 4—4 of Fig. 3;

Fig. 5 is a side elevation of a so-called 35 Saco Pettee building or winding mechanism having my invention applied thereto;

Fig. 6 is a side elevation of a portion of the apparatus shown in Fig. 5 and on a larger scale;

40 Fig. 7 is a plan view of the mechanism shown in Fig. 6;

Fig. 8 is a plan view of a portion of the mechanism shown in Fig. 7, the parts being differently positioned;

45 Fig. 9 is a transverse section, partially in elevation, of the mechanism shown in Fig. 6;

Figs. 10 and 11 are respectively side and end elevations of a portion of the mechanism shown in Fig. 9; and

50 Figs. 12 to 16 inclusive represent somewhat diagrammatically several stages in the manufacture of a cop or yarn package wound or spun in accordance with my invention.

55 Figs. 12 to 16 inclusive represent some-
what diagrammatically several stages in the
manufacture of a cop or yarn package
wound or spun in accordance with my in-
vention.

My invention is peculiarly adapted for ready and convenient application to various types of builder or winding mechanisms, and in the accompanying drawings I have chosen to illustrate its application to two 60 well known types thereof. Within the scope of my invention, however, it may be applied to other types of builder or winding mechanisms.

In accordance with my invention, I provide mechanism whereby the location, size and form of the bunch may be readily controlled. In accordance with the disclosed embodiment of my invention, I provide means whereby the location of the bunch 70 may be raised or lowered upon the yarn receiver; whereby more or less layers of the yarn or other strand may constitute the bunch, thereby varying the thickness thereof; and whereby longer or shorter layers 75 may compose the bunch, thus varying the longitudinal extent thereof. Other advantages of my invention will be pointed out in detail hereinafter.

Referring more particularly to the drawings and first to that form of the invention shown in Figs. 1 to 4 inclusive, I have therein represented a winding or spinning mechanism having a beam 1, a ring rail 2 having spinning rings 3 thereon, a spindle rail 4 85 having suitable spindles 5 mounted thereon, and an arch rail 6 having mounted thereon at suitable intervals depending brackets 7 each having pivoted thereon at 8 a bell crank lever having an arm 9, upon which 90 rides the lower end of the poker arm or rod 10 depending from the ring rail 2 in any customary or suitable manner. The opposite arm 11 of the said bell crank lever is connected to the lifting rod 12. 95

In the usual construction of this type of winding or spinning frame, the lifting rod is directly connected to a chain or flexible element, such as that indicated at 13 in Figs. 1, 2 and 3. In accordance with this 100 form of my invention, I divide or separate the lifting rod into two or more parts, two being shown in this embodiment of my invention, wherein I have represented the part 12 and the second part 14.

The builder cam or element is indicated at 15, it being mounted upon a shaft 16 rotated in any suitable or usual manner in the direction of the arrow thereon. The usual builder arm is indicated at 17 as hav- 110

ing a roll 18 adapted to contact with the surface of the builder cam, thereby to rock the builder arm in the formation of the cop or other yarn receiver. Herein I have 5 represented said builder arm 17 as pivoted at 18' in a suitable girt 19, the said builder arm having pivoted thereon at 20 a scroll gear 21 having a scroll groove or slot 22 adapted to receive therein a roll 23 upon a slide 24 10 mounted in the upwardly extending portion 25 of the builder arm 17. The chain 13 of the lifting rod is connected to said roll 23, and hence in the rotation of the scroll gear 21, it is drawn toward the left, viewing Figs. 1 and 3, thereby lifting the ring rail by suitable increments. In order to 15 rotate the scroll gear 21, I have herein represented a ratchet 26 mounted upon a stud or boss 27, on the upwardly extending portion 25 of the builder arm. Also mounted upon said stud is a pawl carrying lever 28 having pivoted thereon at 29 a pawl 30 to engage the teeth of the ratchet. The 20 opposite arm 31 of said pawl carrying lever extends into proximity to a suitable abutment or operating member 31' mounted upon the arch rail 6 and adjustable therealong by reason of the slot 32 and bolt 33, thus permitting suitable variations in the extent of 25 movement of the ratchet 26 upon each rocking movement of the builder arm 17. A suitable holding pawl 34 is mounted upon the upstanding portion 25 of the builder arm to prevent reverse rotation of the 30 ratchet 26. Also mounted upon the stud or boss 27 is a pinion 35 meshing with the scroll gear 21, whereby upon each rocking movement of the builder arm 17, rotative movement is imparted through the ratchet 35 to the said scroll gear in the direction of 35 the arrow on the latter. Such rotative movement of the scroll gear results in the downward movement of the roll 23, and hence in the movement of the lifting rod 40 toward the left, viewing Figs. 1, 2 and 3, so as to elevate the ring rail.

In Fig. 12, I have represented a yarn receiver at 36, it being here shown as a usual bobbin. In accordance with my invention, 45 I form thereon a bunch which preferably is composed of the first layers of yarn. In said figure, the bunch in a partially completed condition is indicated at 37. Preferably the bunch is built by commencing 50 the layers at a suitable point above the bottom of the bobbin, as for example, at 38, and winding the layers downward in contradistinction to starting said layers at a lower point and winding upwardly. An 55 important feature or characteristic of my invention is its capacity for winding the bunch in this manner. The peculiar advantage of winding the bunch downward is that the lower parts of the subsequently wound 60 layers extending below the bunch can be

unwound more readily and with less danger of breakage than if the winding of the layers constituting the bunch be upward. By winding the bunch downwardly, when the last layer of the bunch is laid, the parts are 70 so positioned that the first longer layer exterior to the bunch can be commenced at the then position of the ring rail. Furthermore it is desirable to wind the bunch upon the downward movement of the ring rail,— 75 that is, from the top of the traverse, since the ring rail runs fastest at the top of each traverse and constantly slower until the bottom of the traverse is reached. If, therefore, the bunch were made from the bottom of the 80 traverse instead of from the top, it would be necessary to move the builder rail up and down more times to make the same size of bunch than is the case when the bunch is wound from the top of the traverse. 85

In the construction shown in Figs. 1 to 4, the bunch is wound downwardly; that is to say, the ring rail is retarded on each downward movement so as to form one layer of the bunch. The ring rail is not in 90 the form of invention shown in these figures, retarded upon its upward movement, but reaches its upward limit upon each upward stroke of the ring rail. As herein set forth, in that form of the invention shown in 95 Figs. 5 to 11, the ring rail is retarded upon its upward movement to effect the formation of the bunch, and hence the bunch is wound upwardly.

Although an important feature and ad- 100 vantage of my invention is the downward winding of the bunch, it is to be understood that within the scope of my invention the bunch may be wound upwardly.

Referring again to that type of mechanism shown in Figs. 1 to 4, by which I wind the bunch as described, I interpose between the members 12 and 14 of the lifting rod the bunch building or forming mechanism, to which my invention more particularly 110 relates.

Therein I have represented the part 14 of the lifting rod as having an upwardly bent end 39, to which is pivotally secured 115 at 40 a lever arm 41, to which at 42 is pivoted the other part 12 of the lifting rod. Also pivoted to said part 14 of the lifting rod at 43 is a short rod or bar 44 passing loosely through a hole 45 in the lever arm 41, and at its end having adjusting nuts 46. 120 Also pivoted to the said lever arm 41 at 47 is an arm 48 having adjustably secured thereto, as by means of a slot and set screw 49, 50, an arm 51 having at its outer end a hook 52. Adjustably secured to the under 125 side of the arm 51 by a slot and screw 53, 54 is a bracket 55. The downwardly extending end 56 of the arm 48 and said bracket 55 are adjustably connected by a bolt 57. By reason of said bolt 57 and the 130

slots and bolts 49, 50, 53 and 54, the effective length of the hook arm 51 may be varied for the purpose of varying or changing the position of the bunch upon the bobbin, that is, for raising or lowering the position thereof.

Preferably secured to one of the uprights or samsons 58 of the mechanism is a bracket 59, extending downwardly from which is a supporting arm 60, shown in dotted lines in Figs. 1 and 3. At the lower end thereof is pivotally mounted at 61 a bell crank lever having arms 62, 63. To the outer end of the arm 62 is pivotally secured an upright bar or member 64 held in position against the bracket 59 by a coil spring 65 connected to the arm 63 of the bell crank lever. Fast upon said bar or member 64 is a block or abutment 66, here shown as tapered and preferably notched as indicated at 67 upon its outer upright edge that is adapted to be engaged by the hook 52. The arm 63 of the bell crank lever is slotted as indicated at 68 and therein is pivoted at 69 with capacity for adjustment lengthwise of said arm 63, a bar or member 70 having deflected portions 71, 72 receiving and supporting a downwardly bent rod 73, the lower end of which is pivoted at 74 to a depending lever arm 75 pivoted at 76 to a bracket 77 on the girt 19. The depending lever 75 is adapted to rest against a pin or stop 78 upon the face of the scroll gear, the position of said pin at the commencement of the winding operation being that shown in Fig. 3. The rotation of the gear permits the lever 75 to move toward the left and consequently through the rod 73, bell crank lever 62, 63 and bar 64 the block 66 is lowered, all as will be more fully hereinafter explained. The rod 73 is adjustably connected in suitable manner to the member 70 and preferably by threading the end 79 of said rod and mounting thereon suitable nuts 80.

Assuming that the winding or spinning action has commenced, if the interposed mechanism described were not provided, then the lifting rod would be moved through its regular length of stroke. Therefore, upon clockwise motion of the builder arm, the chain 13 and said lifting rod will be moved toward the right, thus lowering the ring rail. Because, however, of the interposition of the block or abutment 66, the hook 52 is held upon engagement therewith, thus preventing further movement to the right of the hook carrying member 51. This stops or limits the building motion of the lifting rail, but preferably and in accordance with the illustrated embodiment of my invention, it permits slight further longitudinal movement of the lifting rod member 14 toward the right, the point 47 constituting substantially a pivot about which the

arm 41 may slightly move in a clockwise direction. This permits the slight continued movement of the lifting rod member 14 and at a certain speed. A slight movement in the same direction of the lifting rod member 12 is permitted, but the speed thereof is less than that of the member 14, because the point of connection of the member 12 to the arm 41 at 42 is nearer the pivotal point 47 than is the point of connection 40 of the lifting rod member 14. This results in a slowing down action of the ring rail, which thus has a very slight further movement. The result of the whole operation is, however, such as to limit and determine the point at which the first layer of the bunch terminates, such point being substantially higher than it would have been were not the hook 52 and the coöperating parts present.

The hook 52 rides out of action as the ring rail rises to its upward limit. This allows the abutment or block 66 to rise or fall freely, and at the same time the ring rail winds on a small amount of yarn between the bunch and the upward limit of the yarn traverse, such small amount of winding being of the same character as the main or regular winding throughout the body of the bobbin and is not contracted by the bunch building mechanism.

Upon movement of the lifting rod members 14 and 12 in the opposite direction or to the left, viewing Figs. 1, 2 and 3, the member 41 swings upon the point 42 as a pivot until the lower or free end of said member 41 contacts with the set screws 46, whereupon the further movement of the lifting rod member 14 compels corresponding movement of the lifting rod member 12, said two members continuing to move as a single rigid piece.

By adjusting the hook carrying member 51, as by lengthening the same, the hook will not engage the block or abutment 66 at such an early period in the movement of the lifting rod toward the right, and hence the position of the bunch is lowered. By shortening the hook the position thereof is raised. By adjusting longitudinally the wire 73 with respect to its supporting member 70,—that is, by moving said support to the right viewing Fig. 3,—the bar 64 will be lifted through the bell crank lever 62, 63 carrying with it the block or abutment 66. Therefore the hook 52 in its first movement will engage the block or abutment near its base and hence at a broader part thereof. This adjustment increases the number of layers of the bunch, succeeding layers of the bunch having increasing number of turns, because of the stepped formation of the block or abutment. Conversely, by adjusting the member 70 to the left viewing Fig. 3, the block or abutment 66 is lowered, and hence the number of layers of the bunch is decreased. In other words, the adjustment

of the member 70 to the right or to the left determines the number of reciprocations of the ring rail before the block or abutment 66 is out of action and the regular winding 5 occurs.

By adjusting the pivotal point 69 along slot 68 in lever arm 63 the character of the bunch can be varied. This is due to the fact that such adjustment causes the block 10 to rise higher initially and also because one arm of the bell-crank being shortened, a greater movement of the block will take place on a given amount of rotative movement of the scroll gear 21. Both changes 15 will affect the form of the bunch. It is apparent that a layer wound on the spindle while the bunch-building mechanism is operative consists of two parts, a winding laid on while the hook 52 is not in contact with 20 the block 66 and a contracted winding laid on while it is in contact. The elevation of the block determines at what point the winding is contracted and the relative amount of each sort of winding laid on. As the un- 25 contracted winding is more open than the contracted, the greater the proportion of the traverse devoted to this winding the greater the length of the layer and the more the preliminary winding is spread. Furthermore, 30 on account of the increased movement of the block due to the variation of the length of the lever arm as explained, the "gain" or relative change in position between successive windings will be varied. 35 Therefore, if the bottom point of the first layer is the same, the bottom point of the next layer is lower on the spindle when the pivot point 69 has been moved along the slot 68 than it would have been had it been 40 allowed to remain at the end of the slot. This evidently causes a spreading of the bunch.

It will be understood that as the winding progresses in the formation of the bunch, 45 the scroll gear 21 is turned in a clockwise direction, thus moving the pin 78 in such direction and permitting the rod 73 and the lever arm 75 to follow the same under the influence of the spring 65. This results in 50 a continued downward movement of the block or abutment 66, and hence the further laying of the bunch. When the block or abutment has been sufficiently lowered so that the hook 52 no longer contacts there- 55 with, then the regular winding is proceeded with. When this winding is being carried on it will be understood that the lever 41 is continuously in contact with the abutment nuts 46, the member 12 being, as it were, 60 connected to the member 14 by a triangular yoke. The tensile connection between the builder motion and the bell-crank 11 is in effect a single piece, the arms 48 and 51 and hook 52 being entirely inoperative.

65 In Figs. 5 to 11 inclusive, I have repre-

sented my invention as applied to the so-called Saco Pettee winding or builder mechanism. In the chosen embodiment of my invention therein illustrated, the bunch is built or wound upwardly in contradistinction to the downward building thereof characteristic of that form of the invention shown in Figs. 1 to 4 inclusive.

Referring again to Figs. 5 to 11 inclusive, the beam is represented at 1, the ring rail at 2, the spinning rings at 3, the spindle rail at 4 and the spindles at 5. These may be of any suitable character. Pivoted in a bracket 81 attached to and depending from the spindle rail 4 is a lifting lever 82, upon 75 the outer end of which rides the lower end of the poker or lifting arm or rod 83 connected at its upper end to the ring rail 2 in usual manner. The lever 82 is provided with an upwardly extending arm 84 having 80 thereon an arc shaped member 85 to which at 86 one end of the builder or let-off chain 87 is connected. The chain, which corresponds in function to the lifting rod of that form of the invention shown in Figs. 1 to 4, 85 is likewise formed in sections, herein two, one of which is shown at 87 and the other at 88. The member 88 of the chain has a portion 89 thereof turned at right angles so as to encircle a sheave or guide pulley 90 90 loosely pivoted upon a stud 91 on the builder arm 92 itself pivoted at 93 upon a suitable bracket 94 upon the frame of the mechanism. Fast with the sheave 90 is a worm gear 95 meshing with which is a worm 96 100 mounted in suitable bearings upon the builder arm 92, the latter having a counter-weight 97 and a roll 98 in constant contact with the edge of the builder cam 99 mounted upon a shaft 100 driven in any suitable or 105 usual manner. Fast upon the shaft of the worm 96 is a suitable ratchet 101 and pivoted co-axially therewith is a pawl carrying arm 102, the pawl 103 of which has an 110 upward movement of the builder arm to strike a projection or pin 105 by which the ratchet is turned one or more teeth, thereby letting off a predetermined amount of chain from the sheave 90. In this manner, the 115 chain is constantly let off during the building operation, and therefore the ring rail 2 is incrementally raised in a well known manner.

The member 88 of the builder chain passes 120 about a sheave 106 mounted for rotation in a bracket 107 upon the builder or spinning frame head. Interposed between and connected with the two members 87, 88 of the builder chain is a mechanism which modifies 125 the action of the chain and results in the building of the bunch.

Referring more particularly to Figs. 7 and 8, I have therein represented the portion 89 of the builder chain as having piv- 130

- oted thereto an elongated link 108 to the outer end of which at 109 are pivoted two bars or rods 110, 111. Said rods or bars 110 or 111 are pivotally connected at 109.
- 5 To the outer end of the rod or bar 110, at 112, is pivoted a transverse rod or bar 113 having near its outer end a pin 114 taking in a slot 115 in the rod or bar 111. To the rod or bar 113 intermediate its end is connected the member 87 of the builder chain.
- Pivottally secured to the rod or bar 113 intermediate its ends at 116 is a rod or bar 117, the effective outer end 118 whereof is adapted to impinge against the head 119
- 15 of a slide member 120 mounted for sliding movement in guides 121, 122. Attached to the slide 120 is a spring 123, an end of which is connected to a pin 124 on the bracket 107. Attached to the rod or bar 113 is a spring
- 20 125, the opposite end thereof being connected to the projection 108^x of the link 108. If desired the parts 108, 108^x and 110 may all be made in one piece.
- Upon the bracket 107 and extending trans-
- 25 versly of the slide 120 is a guide 126, wherein is mounted for sliding movement a block or abutment 127 corresponding in function to the block or abutment 66 in that form of the invention shown in Figs. 1 to 4 includ-
- 30 sive. Passing through an upstanding lip 128 on said block or abutment is a rod 129 having set screws 130 upon the outer threaded end thereof, as shown most clearly in Figs. 7 and 9. Fast upon the said rod is
- 35 a collar 131 and between the said collar and the lip 128 is a coil spring 132 acting to hold the nuts 130 against the lip. As shown most clearly in Figs. 6 and 7, the rod or bar 117 is provided with an upstanding lip 133
- 40 and is adjustably connected by slot 134 and bolt 135 to the main portion 118 of said rod or bar 117. Also connected thereto in a suitable manner is a bracket piece 136 and connecting the said bracket pieces is a bolt
- 45 137 provided with a threaded portion having nuts 138 thereon, and a head 138' engaging the bracket piece 136. In this manner the effective length of the rod or bar 117, 118 may be varied. This adjustment
- 50 corresponds to the adjustment shown in Figs. 2 and 3 for varying the effective length of the hooked member 51, 52, by means of which the position of the bunch is varied.
- Fast upon the sheave 90 is an upstanding
- 55 member or bracket 139 having a free end 140. Pivoted upon said bracket at 141 is a finger 142 connected to the free end 140 of the bracket 139 by coil spring 143. The parts 139, 140, 141, and 142 may, if desired,
- 60 all be made in one piece. Pivoted upon the builder arm 92 at 144 is a lever 145 having pivoted thereto at 146 the rod 129. Also pivoted upon said lever 145 at 147 is a rod 148, the outer end of which is supported in
- 65 a guiding bracket 149 secured to and ex-
- tending upwardly from the builder arm 92. Upon the outer threaded end of said arm 148 is an abutment piece 150 held in adjusted position thereon by nuts 151. The rod 148 is held in position with respect to 70 the guide arm 141 by a suitable coil spring 152. The finger 142 is provided with a tip 153 held in engagement by the spring 143 with the abutment piece 150 at the commencement of the operation. As the building up of the cop or yarn package continues, the chain member 89 is let off from the sheave 90 and the finger 142 is intermittently turned in a clockwise direction. The clockwise movement of the finger 142 80 permits the rod 148 to move to the right (Fig. 9) under the influence of spring 152. This movement rocks the link 145 on pivot 144 and moves the rod 129 to the right in Fig. 9 or downwardly in Fig. 7 thus lowering 85 the block 127. The adjustment of the abutment piece 150 is for the purpose of varying the size of the bunch and corresponds to the adjustment of the rod 73 with relation to the initial position of the pin 78, 90 since both determine the initial position of the abutment block and consequently the number of reciprocations before it is withdrawn from action.
- It has previously been stated that the rod 95 129 is connected to the block or abutment 127 by nuts 130, thus permitting a change in initial position of the block or abutment 127. This adjustment is for the purpose of controlling the number of layers in the 100 bunch and corresponds to the adjustment of the block or abutment 66 in that form of the invention shown in Fig. 3 through the slot 68.
- The operation of this device can be clearly 105 understood by reference to Fig. 7. Suppose the parts to be in the position there shown and the chain 87 to be moving to the left to raise the ring rail. The lever 113 is rocked on the pivot 116 which is held stationary because of the support of the piece 118 on 119 which in turn is held by the block 127. The movement of 87 is consequently small relative to the movement of 108 and the rail is retarded. Toward the end of the stroke, 110 however, the member 118 will be drawn away from 119 and the frame will be winding turns of the ordinary character, the action being exactly like that of the hook 52 riding out of contact with block 66. The 120 movement of 118 away from 119 will relieve the pressure on block 127 and it may move (downwardly in Fig. 7) under the action of the mechanism 142, 148, 145 and 129 (see Fig. 9) as just described. On the return 115 stroke (to the right in Fig. 7) therefore the block 127 will come into action to retard the rail at a later point and this will continue until the block is entirely withdrawn from action and the regular winding begun.

It will be observed that in both forms of the invention is disclosed a floating tensile connection between the builder motion and the yarn guiding means, said connection being an element which in one case partakes of the form of a chain and in the other of a lifting rod. In both cases, these elements are divided into a plurality of members, preferably two, and interposed between or 10 operatively connected thereto is the building modifying means, the action of which is to form a bunch. In the preferred form of the invention, the bunch is built downwardly, and in the other form thereof it is built upwardly. In each case, the modifying or bunch forming mechanism is of simple construction and may be readily applied to existing types of mechanisms with little change.

20 Although I have shown but two types of spinning or building frames, it is obvious that my invention may be applied to other types thereof, and that my invention is not restricted to its use in connection with those illustrated.

In Fig. 12, the bobbin or other support is shown as having wound thereon the initial portion of the bunch 37. In Fig. 13, I have represented the completed bunch at 30 154. In Fig. 14, I have represented a further stage in the building up of the cop, the bunch being overlaid by certain layers 155 of the regular traverse, and in Fig. 15, I have represented the commencement of 35 the formation of the cylindrical portion of the cop. In Fig. 16 I have represented at 157 the complete cop. These several representations are diagrammatic merely.

In the formation of the cop or yarn package in accordance with my invention, the 40 yarn is laid in a series of layers of closely wound coils, and between succeeding layers is a binding layer of more open coils. Bunches have heretofore been formed by retarding the ring rail during its operation at the bottom of the bobbin. This retarding action also results in an unsatisfactory package of yarn, inasmuch as when the rail stopped for any substantial length of time, 45 it would result in piling the coils of yarn up at one point and thus making a very abrupt and ineffective bunch. Furthermore in such construction the ring rail, after such retardation, has been given a very sudden 50 movement to begin the formation of the regular traverse. This also has resulted in the formation of an unsatisfactory yarn package. In accordance with my invention, and assuming the ring rail to be the movable 55 element and the yarn receiver to be stationary, the ring rail is moved through a series 60 of short traverses, preferably of progressively increasing length to effect the laying of the bunch and immediately thereafter the 65 formation of the regular traverses is com-

menced. Referring to that form of the invention shown in Figs. 1 to 4, the bunch is formed of a series of downwardly wound layers, and between the successive layers are the so-called binding layers which are upwardly wound. The last winding layer of the bunch finds the ring rail positioned so as to lay the yarn at the bottom of the bunch, and immediately thereafter the ring rail is raised so as to lay the loose binding 70 layer, such layer continuing to the top of the bunch or very slightly thereabove, and immediately thereafter the first regular traverse layer is positioned, this continuing preferably to the point shown in Fig. 14. 80 It will therefore be observed that in accordance with my invention, I cause a series of constant to and fro relative traverse movements between the yarn guiding means and the receiver, the said series including a plurality of short bunch-forming layers and a plurality of regular traverse layers, the latter immediately succeeding the formation of the former. The movement of the ring rail is an easy, gradual one, in which the bunch 85 is laid by traverses of progressively increasing length, the last of which is immediately succeeded by an easy motion of the ring rail in the first of the regular long layers.

In that form of the invention shown in 90 Figs. 5 to 11 inclusive, the operation is merely reversed in that the winding is upward. In the claims I refer to the bunch as an initial bunch, though within the scope of the invention, it may be preceded by one 95 or more layers of longer traverse. Preferably however, the bunch is laid upon a bare bobbin or other carrier.

From the foregoing description, it will be evident that in accordance with my invention, I have provided means whereby the bunch may be formed at any desired portion on the bobbin or other support, and whereby the size and form thereof may be varied. Obviously these several features of 105 my invention may be employed singly or together, and my invention is not restricted to their conjunctive use.

Having thus described one illustrative embodiment of my invention, I desire it to 110 be understood that although specific terms are employed, they are used in a generic and descriptive sense and not for purposes of limitation, the scope of the invention being set forth in the following claims.

1. In a traverse motion for winding yarn on yarn receivers, a yarn receiver support, yarn guiding means, means to cause a relative to and fro movement between the yarn guiding means and said receiver, and said 115 movement comprising a number of preliminary, bunch forming strokes and a succeeding number of body-forming strokes and means to retard said movement during a 120 part of each of said preliminary strokes. 130

2. In a traverse motion for winding yarn on yarn receivers, a yarn receiver support, yarn guiding means, means to cause a relative to and fro movement between the yarn guiding means and said receiver and said movement comprising a number of preliminary, bunch forming strokes and a succeeding number of body-forming strokes and means to retard said movement during a part of each of said preliminary strokes and means to change the commencement point of said retardation.
3. In a traverse motion for winding yarn on yarn receivers, a yarn receiver support, yarn guiding means, means to cause a relative to and fro movement between the yarn guiding means and said receiver, and said movement comprising a number of preliminary, bunch forming strokes and a succeeding number of body-forming strokes and means to retard said movement during a part of each of said preliminary strokes and means to vary the number of strokes so modified.
4. In a traverse motion for winding yarn on yarn receivers, a yarn receiver support, yarn guiding means, means to cause a relative to and fro movement between the yarn guiding means and said receiver, and said movement comprising a number of preliminary, bunch forming strokes and a succeeding number of body-forming strokes and means to retard said movement during a part of each of said preliminary strokes and means to change the commencement point of said retardation and to vary the number of strokes so modified.
5. In a traverse motion for winding yarn on yarn receivers, a yarn receiver support, yarn guiding means, means to cause a relative to and fro movement between the yarn guiding means and said receiver, and said movement comprising a number of preliminary, bunch forming strokes and a succeeding number of body-forming strokes and means to retard said movement during a part of each of said preliminary strokes while the guiding means is nearer the receiver support.
6. In a traverse motion for winding yarn on yarn receivers, a yarn receiver support, yarn guiding means, means to cause a relative to and fro movement between the yarn guiding means and said receiver, and said movement comprising a number of preliminary, bunch-forming strokes and a succeeding number of body-forming strokes and means to retard said movement during a part of each of said preliminary strokes while the guiding means is nearer the receiver support, and means to change the commencement point of said retardation.
7. In a traverse motion for winding yarn on yarn receivers, a yarn receiver support, yarn guiding means, means to cause a relative to and fro movement between the yarn guiding means and said receiver and said movement comprising a number of preliminary, bunch forming strokes and a succeeding number of body-forming strokes and means to retard said movement during a part of each of said preliminary strokes while the guiding means is nearer the receiver support, and means to vary the number of strokes so modified.
8. In a traverse motion for winding yarn on yarn receivers, a yarn receiver support, yarn guiding means, means to cause a relative to and fro movement between the yarn guiding means and said receiver and said movement comprising a number of preliminary, bunch forming strokes and a succeeding number of body-forming strokes and means to retard said movement during a part of each of said preliminary strokes while the guiding means is nearer the receiver support and to vary the number of strokes so modified.
9. In a traverse motion for winding yarn on yarn receivers, yarn receiving supports, yarn guiding means, a builder element, a floating tensile, traverse-causing connection between said builder element and said yarn guiding means comprising a linkage to reduce the motion of one end of said connection relatively to the other, means carried by said connection to hold said linkage inoperative and means apart from said connection and controlled by the builder element to operate the linkage.
10. In a traverse motion for winding yarn on yarn receivers, yarn guiding supports, yarn guiding means, a builder element, a floating tensile, traverse-causing connection between said builder element and said yarn guiding means comprising a linkage to reduce the motion of one end of said connection relatively to the other, means carried by said connection to hold said linkage inoperative and means apart from said connection and controlled by the builder element to operate the linkage at different periods of the motion of said yarn guiding means.
11. In a traverse motion for winding yarn on yarn receivers, a yarn receiver support, yarn guiding means, means to cause a relative to and fro movement between the yarn guiding means and said receiver, and traverse modifying means coöperating to form a bunch of wound layers of lengths gradually increasing in downward direction only.
12. In a traverse motion for winding yarn on yarn receivers, a yarn receiver support, yarn guiding means, means to form an initial bunch of short layers of lengths gradually increasing downwardly only, and means to form regular traverse layers immediately succeeding the formation of the bunch.
13. In a traverse motion for winding yarn

on yarn receivers, yarn receiver supports, 5
yarn guiding means, a builder element, a
traverse-causing tensile connection between
said element and said yarn guiding means,
and means comprising a mechanism suspended
between the terminals of said connection
and a coöperating mechanism apart from
said connection and controlled by said
builder element to cause the formation of a
10 yarn bunch.

14. In a traverse motion for winding yarn
on yarn receivers, yarn receiver supports,
yarn guiding means, a rotatable builder ele- 15
ment, a traverse-causing tensile connection
between said element and said yarn guiding
means, and means comprising a mechanism
suspended between the terminals of said
connection and a coöperating mechanism taking
20 motion directly from said builder element
independently of said connection to cause
the formation of the yarn bunch.

15. In a traverse motion for winding
yarn on yarn receivers, yarn receiver sup- 25
ports, yarn guiding means, a rotatable
builder element, a divided traverse-causing
tensile connection between said element and
said yarn guiding means, bunch forming
means comprising a mechanism suspended
30 by the divisions of said connection, and a
coöperating abutment member independent
of said connection.

16. In a traverse motion for winding
yarn on yarn receivers, yarn receiver sup- 35
ports, yarn guiding means, a rotatable
builder element, a traverse-causing tensile
connection suspended between said element
and said yarn guiding means, and an abut-
ment member actuated independently of the
40 movement of said connection and positioned
to coöperate with said connection and to re-
strict its movement.

17. In a traverse motion for winding yarn
on yarn receivers, yarn receiver supports,
yarn guiding means, a rotatable builder ele- 45
ment, a traverse-causing tensile connection
between said element and said yarn guiding
means, and an abutment member actuated
independently of the movement of said
connection and positioned to engage said
50 connection and to prevent full movement
thereof.

18. In a traverse motion for winding
yarn on yarn receivers, yarn receiver sup- 55
ports, yarn guiding means, a rotatable
builder element, a traverse-causing tensile
connection between said element and said
yarn guiding means, and an abutment mem-
ber actuated independently of the movement
60 of said connection and having a wedge por-
tion positioned to co-act with said connec-
tion and to prevent full movement thereof.

19. In a traverse motion for winding yarn
on yarn receivers, yarn receiver supports,
yarn guiding means, a rotatable builder ele- 65
ment, a traverse-causing tensile connection

between said element and said yarn guiding
means, and an abutment member actuated
independently of the movement of said con-
nection and having a stepped portion posi- 70
tioned to engage said connection and to pre-
vent full movement thereof.

20. In a traverse motion for winding yarn
on yarn receivers, yarn receiver supports, a
yarn guiding means, a rotatable builder ele- 75
ment, a floating traverse-causing tensile con-
nection between said element and said yarn
guiding means, and an abutment member
actuated independently of the movement of
said connection and having a tapered por- 80
tion positioned to co-act with said connec-
tion and to prevent full movement thereof.

21. In a traverse motion for winding yarn
on yarn receivers, yarn receiver supports, a
yarn guiding means, a rotatable builder ele- 85
ment, a traverse-causing tensile connection
between said element and said yarn guiding
means, an abutment member actuated inde-
pendently of the movement of said connec-
tion and having a wedge portion positioned
90 to engage said connection to prevent full
movement thereof, and means to adjust the
abutment to vary the position of its wedge
portion.

22. In a traverse motion for winding yarn
on yarn receivers, yarn receiver supports, 95
yarn guiding means, a rotatable builder ele-
ment, a traverse-causing tensile connection
between said element and said yarn guiding
means, bunch forming means comprising a
mechanism interposed between the ends of 100
said tensile connection, an abutment held
against movement with said connection, and
a lengthwise, adjustable member extending
from said interposed mechanism and adapt-
ed to engage said abutment in the formation 105
of the bunch.

23. In a traverse motion for winding yarn
on yarn receivers, yarn receiver supports, a
yarn guiding means, a rotatable builder ele- 110
ment having a positioning pin, a traverse-
causing tensile connection between said ele-
ment and said yarn guiding means, an abut-
ment member, means carried by said connec-
tion to coöperate with said block or abut- 115
ment member in the formation of the bunch,
and means associated with said abutment
member to control the same and extending to
said positioning pin.

24. In a traverse motion for winding yarn
on yarn receivers, yarn receiver supports, 120
yarn guiding means, a rotatable builder ele-
ment having a position determining pin,
a traverse-causing tensile connection between
said element and said yarn guiding means
and having a projecting bunch forming 125
member, an abutment member positionable
in the path of said projecting bunch form-
ing member, and means to control said abut-
ment member extending from the same to
and positionable by said pin. 130

25. In a traverse motion for winding yarn on yarn receivers, yarn receiver supports, yarn guiding means, a rotatable builder element, a divided traverse-causing tensile connection operatively connected to said builder element and said yarn guiding means, an abutment member upon a fixed part of the mechanism, a hook connected to one of said divisions and adapted 5 to engage said abutment to limit the movement of the division in the formation of a bunch, and means to vary the position of said abutment member.
26. In a traverse motion for winding 10 yarn on yarn receivers, yarn receiver supports, yarn guiding means, a rotatable builder element, a traverse-causing tensile connection operatively connected to said builder element and said yarn guiding 15 means, bunch forming means including an abutment member upon a fixed part of the mechanism, a hook extending from said connection and adapted to engage said abutment in the formation of a bunch, and 20 means to vary the length of said hook.
27. In a traverse motion for winding 25 yarn on yarn receivers, yarn receiver supports, yarn guiding means, a rotatable builder element, a traverse-causing tensile connection operatively connected to said builder element and said yarn guiding 30 means, bunch forming means including an abutment member upon a fixed part of the mechanism, a hook extending from said connection and adapted to engage said abutment in the formation of a bunch, and 35 operating means to vary the position of the bunch and the size thereof.
28. In a traverse motion for winding 40 yarn on yarn receivers, yarn receiving supports, yarn guiding means, a builder element, a divided, traverse-causing, tensile connection operatively connected to said builder element and said yarn guiding means, a 45 lever suspended between divisions of said tensile connection, and means independent of said connection coöperating with the lever to cause it to give differential motion to said divisions.
50. 29. In a traverse motion for winding yarn on yarn receivers, yarn receiving supports, yarn guiding means, a builder element, a divided, traverse-causing, tensile connection operatively connected to said builder 55 element and said yarn guiding means, a lever suspended between divisions of said tensile connection and means acting through the resistance of a stationary part of the mechanism automatically to check said lever 60 in fixed relation to said part to cause it to give differential motion to said divisions.
30. In a traverse motion for winding yarn 65 on yarn receivers, yarn receiving supports, yarn guiding means, a builder element, a divided, traverse-causing, tensile connection operatively connected to said builder and said yarn guiding means, a lever suspended between divisions of said tensile connection and means acting through the resistance of a stationary part of the mechanism automatically to check said lever 70 at a series of points in fixed relation to said part to cause it to give differential motion to said division.
31. In a traverse motion for winding 75 yarn on yarn receivers, yarn receiving supports, yarn guiding means, a rotatable builder element, a floating, traverse-causing, tensile connection between said element and said yarn guiding means, and an abutment member having a tapered portion positioned to co-act with such connection and to prevent full movement thereof and means engaging 80 said builder element and actuated by the rotation thereof to change the co-acting part 85 of said tapered portion.
32. In a traverse motion for winding 90 yarn on yarn receivers, yarn receiver supports, yarn guiding means, a rotatable builder element, a traverse-causing tensile connection between said element and said yarn guiding means, bunch forming means comprising a mechanism interposed between the ends of said tensile connection, an abutment, and a length-wise adjustable member extending 95 from said interposed mechanism and adapted to engage said abutment in the formation of the bunch, and means engaging said builder element and actuated by the rotation thereof to shift the point of 100 engagement of said abutment and member.
33. In a traverse motion for winding 105 yarn on yarn receivers, yarn receiver supports, yarn guiding means, a builder element for imparting a traverse to the yarn guiding means, an operating connection between said element and guiding means and a device independent of said connection, movable into and out from the path thereof under control of the builder element and co-operating therewith to reduce the traverse 110 stroke of the yarn-guiding means.
34. In a traverse motion for winding 115 yarn on yarn receivers, yarn receiver supports, yarn guiding means, a builder element for imparting a traverse to the yarn guiding means, an operating connection between said element and guiding means, and a tapered abutment independent of said connection and movable by said builder element in the 120 traverse-causing operation thereof across the path of the connection to coöperate with the same to reduce at varying periods the traverse stroke of the yarn guiding means.
35. In a traverse motion for winding 125 130 yarn on yarn receivers, yarn receiver supports, yarn guiding means, a builder element for imparting a traverse to the yarn guiding means, an operating connection between said element and guiding means and a de-

vice movable into and out from the path thereof and coöperating therewith to reduce the traverse stroke of the yarn guiding means and a train of mechanism connecting the builder element and said device whereby the former directly controls the latter.

36. In a traverse motion for winding yarn on yarn receivers, yarn receiver supports, yarn guiding means, a builder element for imparting a traverse to the yarn guiding means, an operating connection between said element and guiding means, a device independent of said connection and held against movement therewith, a linkage between the builder element and said device whereby movement of the former will move the latter transversely of the path of the connection, said linkage being adjustable, and means to check said connection by engagement with said device to modify the motion thereof.

37. In a traverse motion for winding yarn on yarn receivers, yarn receiver supports, yarn guiding means, a builder element for imparting a traverse to the yarn guiding means, an operating connection between said element and guiding means, a device independent of said connection and held against movement therewith, a linkage between the builder element and said device whereby movement of the former will move the latter transversely of the path of the connection, said linkage being adjustable, and

means to check said connection by engagement with said device to modify the motion thereof, said means being adjustable to change the time of engagement.

38. In a traverse motion for winding yarn on yarn receivers, a yarn receiver support, yarn guiding means, means to cause a relative to and fro movement between the yarn guiding means and said receiver, said movement comprising a number of preliminary bunch forming strokes of progressively increasing amplitude or length and a succeeding number of body-forming strokes and means to retard said movement during a part of each of said preliminary strokes.

39. In a traverse motion for winding yarn on yarn receivers, a yarn receiver support, yarn guiding means, the builder 21, the connection 14, 12 between said builder and guiding means, the linkage 41 carried thereby, the member 66 carried by the frame and controlling the movement of said linkage and the means 73—75 coöperating with said builder to govern the member 66 substantially as shown and for the purpose described.

In testimony whereof, I have signed my name to this specification, in the presence of two subscribing witnesses.

JOHN B. DONOVAN.
